DETACHABLE ENDGATE

John R. Hansen, Manning, Iowa

Application February 24, 1936, Serial No. 65,508

3 Claims. (Cl. 296—52)

This invention relates to a novel and structurally improved endgate susceptible of use in conjunction with commodity transportation vehicles and conveyances, such as for example wagons of the wooden box type utilized for handling grain or the like.

Needless to say, I am aware of the fact that the art to which the invention relates is characterized by countless different forms and styles of endgate constructions of the built-in type as well as the detachable style. Likewise, it is admittedly old to utilize a unitary endgate structure fashioned with a sliding trap door or closure and companion frame structure.

In perfecting the principles of the present invention and reducing to actual practice the preferred embodiment thereof I have evolved and produced an assemblage which, as a complete structure, is believed to be an improvement on similar prior art devices particularly in that it is susceptible of being made up from wood or equivalent economical material and complementary parts.

To consider the alleged novelty from another viewpoint, it will be appreciated that what I have invented is a substantially all-wood coordination of properly selected and allocated parts designed to promote ease of operation, dependability and efficiency, to afford the requisite grain-tight result and to otherwise provide an assemblage aptly fitted for the purposes intended and such as to receive unqualified endorsement by the trade and users in general.

Briefly, and from a structural standpoint, the preferred embodiment of the invention depends largely for distinctiveness and individuality on the adoption and use of a frame structure easily attachable to a conventional box type wagon wherein said structure is provided with stabilizing battens grooved to serve as tracks for a slideable closure panel, said closure panel being in turn properly reinforced and having associated therewith a uniform stress-distributing raising and lowering lever and retaining unit.

Other features and advantages will become more readily apparent from the following description and drawing.

In the drawing:

Figure 1 is a perspective view of the endgate per se with the door or panel swung down to closed position and locked;

Figure 2 is a view similar to Figure 1 showing the lever unlocked and partially swung up to initially slide the panel up to open position;

Figure 3 is a view showing the gate-panel swung up completely to open position;

Figure 4 is a fragmentary corner view of a portion of a wagon body showing how the gate is detachably and pivotally bolted thereto.

The relatively stationary frame portion of the assembly is denoted by the numeral 5. It comprises what may be described as a board 6 having depending vertical hand-extensions which function as retention flanges 7 when used in the wagon box or body 8 as shown in Figure 4. These portions are so cut as to define the discharge opening which is normally closed by the vertically sliding gate-panel or trap door 9. This is in the form of a rectangular panel of appropriate proportion and is vertically slideable in the guideways formed in the vertical cleats or battens 10. These battens are nailed in spaced parallelism to the end portions of the frame and are of a height commensurate with the height of the frame. Nailed transversely and in spaced parallelism to the outer side of the panel 9 and in predetermined spaced relation from the cleats 10 are cross-pieces or supplementary cleats 11. These are of a length even with the transverse width of the panel. Incidentally, the combined thickness of the panel 9 and cross-pieces 11 is equal to the thickness of the cleats 10 to provide the desired flush intimate nesting relationship shown in Figure 1.

I next call attention to that part or unit indicated by the numeral 12 and conveniently described as the operating unit. It is in the nature of a lever of general U-shaped form and includes a pair of uniform end bars 13, these being pivotally connected as at 14 to the extreme upper end of the cleats 10 to allow the panel to swing completely up to open position as shown in Figure 3. These parts 13 correspond in length to the cleats 10 and in thickness to the supplementary cleats 11 insuring requisite flush cooperation as shown in Figure 1. They are connected together for simultaneous operation by a connecting strip 15 nailed to the lower end portions and having its ends 16 extending beyond the end members 13 to bear in tight contact against the cleats 10.

Incidentally, the numeral 16 designates a pivoted hook or clip for the panel which is detachably cooperable with the connecting strip or handle 15. This allows the handle to serve as a locking member. The operating connection between the supplementary cleats 11 and the arm or end bar 13 is made through the instrumentality of appropriate pivotally connected metal strap links 17.

The operation of the structure is unquestionably clear from the description and drawing.

The important thing to be borne in mind is that the whole structure is substantially made up of wood with the exception of the clip 16 and the links 17. All parts have been carefully selected and matched for uniform coordination. Perfect balance and ease of operation is insured through the instrumentality of this special adaptation of parts. The respective cleats 10 and 11 reinforce the parts to which they are attached and contribute their respective functions as used in conjunction with the lifting and lowering lever-unit 12. Taking everything into consideration, it will be discerned that I have here developed an economical, well-balanced and reliable arrangement.

It is generally desirable to provide attaching bolts 18 and retaining nuts 19 to properly mount the frame structure 5 in the keeper means 20 on the vertical side walls of the wagon body 8 as shown in Figure 4. This is done by connecting the bolts to the upper end portion of the cleats 10 but at points downward from the pivot 14. This arrangement is brought out in Figure 4 with sufficient clarity.

It is thought that the description taken in connection with the drawing will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

1. An endgate comprising a frame in the form of a board having a notch cut in its lower end portion to define a gate opening, a pair of duplicate vertical battens secured to the rear face of said board and rabbeted to form guide tracks, a closing gate for said gate opening in sliding contact with said board and having its end portions slidably mounted in said guide tracks, vertical cross-pieces connected to the outer face of said gate and spaced from said battens, a pair of arms pivotally connected at their upper ends to the extreme upper ends of said battens and nested in the space between the battens and adjacent cross-pieces, pivoted link connections between the intermediate portions of the arms and upper end portions of said cross-pieces, a tie-bar be-

tween the lower end portions of said arms, and a retention clip on said gate engageable with said tie member in the manner and for the purposes described.

2. An endgate of the class described comprising a frame provided with a gate opening, a pair of duplicate vertical battens secured to the normally outer face of said gate and provided with guide channels, a closing gate for said gate opening sliding in said channels and in contact with the frame, a pair of duplicate arms of a length substantially equal to the vertical height of said frame, said arms being pivotally connected at their upper ends to the corresponding ends of said battens and being foldable down alongside of and in contact with the battens, a handle-forming tie-bar connected with the lower end portions of said arms and projecting at right angles beyond the longitudinal dimensions of said arms to rest in contact with said battens, an operating link connection between the intermediate portions of the arms and said closing gate.

3. A wooden endgate comprising a main rectangular gate board having a gate opening therein, a pair of duplicate vertically disposed battens secured to the rear face of said board and having their inner longitudinal edges rabbeted to form guide tracks, said battens being spaced inwardly from the opposite vertical ends of said board, a closing gate in sliding contact with the board and cooperable with said opening and having its end portions slidably mounted in said guide tracks, relatively short vertical wooden battens extending transversely across the end portions of the gate and disposed in spaced parallelism to said first-named battens, a pair of wooden arms pivotally connected at their upper ends to the corresponding ends of said first-named batten, said arms being of a length corresponding to said first-named batten and of a width to fold into the spaces between the first and second-named battens, link connections between the intermediate portions of the arms, and said second-named batten, and a wooden tie bar connected with the lower free end portions of said arms, the ends of the tie bar extending at right angles beyond the arms whereby to permit the tie bar to simultaneously rest on the batten when the gate is closed.

JOHN R. HANSEN. 50
